UNITED STATES PATENT OFFICE.

CHARLES REINEKE, OF NEW YORK, N. Y., ASSIGNOR TO THE REINEKE MOTOR CORPORATION, OF NEW YORK, N. Y., A CORPORATION OF DELAWARE

INTERNAL-COMBUSTION ENGINE.

Application filed July 23, 1924. Serial No. 727,731.

This invention relates to improvements in internal combustion engines and more particularly to a novel internal combustion engine for aero, automobile or marine use.

5 The primary object of the invention is to provide a novel explosive engine of the opposed piston type, and in which the crank shaft is located at the end of the cylinder. The cylinder has off-set portions in line with 10 the shaft, and the off-set is sufficient only to allow the upper piston to act on a projection normally on the underside of the drive shaft, while the lower piston acts on a projection normally on top of the drive shaft, thus permitting 15 simultaneous push and pull action, and causing an even torque on the shaft bearings. The engine also includes means having rigid rods for connecting the upper piston to the projection on the underside of the shaft. By employing means permitting even 20 pull and push strokes, roller or ball bearings may be used in the connections between the drive shaft and pistons. The off-set cylinder construction enables me to provide a compact 25 opposed piston engine, in which all of the lubrication may take place at the point where the drive shaft is located. In other words, the drive shaft being located at one end of the cylinder, a crank case may be placed at this 30 location and the connecting rod bearings may run in an oil bath. The present construction also permits a three cylinder structure, thus giving the best torque (three points to the drive shaft).

35 Another object of the invention is to provide an opposed piston engine in which each piston is rigidly connected to its piston rod, so that the wrist pin and its bearing may be eliminated from the piston, thus allowing 40 uniform expansion and contraction of both pistons. As the pistons are rigidly connected to their rods, these rods are guided in a straight line, so that there will be no piston 45 slap in the present construction.

45 A further object is to furnish an opposed piston engine which may be quickly removed from its supporting frame or foundation. The construction is such that the cylinder block may be detached from the crank case 50 by removing four screws and detaching the connecting rods of the upper piston. Consequently for automobile use, the entire cylinder block may be expeditiously removed when necessary, and a new block may be 55 quickly put in its place.

With the foregoing objects outlined and with a number of other objects in view which will appear as the description proceeds, the invention consists in the novel features hereinafter described in detail, illustrated in the accompanying drawings and more particularly pointed out in the appended claims.

Referring to the drawings;

Fig. 1 is a longitudinal vertical sectional view of a two cylinder engine of my improved 65 construction.

Fig. 2 is a transverse vertical sectional view taken on line 2—2 of Fig. 1.

Fig. 3 is a horizontal sectional view taken 70 on line 3—3 of Fig. 1.

Fig. 4 is a side view of the open frame which is connected to the upper piston of each cylinder and engages a bearing ring on the engine shaft.

Fig. 5 is a sectional view of a detail taken 75 on line 5—5 of Fig. 4.

In the drawings 1 designates a base plate casting which forms a foundation for the cylinder block, and a cover for the crank case. This plate is provided at each side with outwardly extending arms 2, each having an aperture 3 at its outer end to receive a bolt or screw employed in fixing the plate on any suitable support. If the engine is used 80 for an automobile, the arms 2 will be secured to the chassis. The plate, as best shown in Figs. 1 and 2, is provided at each end with legs 4, of fork shape, the crotch of the fork as shown in Fig. 1, receiving a roller bearing 5 held in place by a saddle plate 6 secured by 85 bolts or screws 7. Thus the base plate supports the bearings 5 for the drive shaft 8, and the upper portions 9 of the legs form partially the ends of the crank case or oil chamber 10. The legs 4 have vertical flanges 90 11 to which side plates 12 are secured by screws 13. The plates 12 form the sides of the chamber 10, and each plate, as best shown in Fig. 2, has a horizontal ledge 14 provided with apertures to receive bolts 15, which secure an oil pan 16 in position. From the foregoing it will be obvious that the entire bottom of the chamber 10 is opened, when the pan 16 is removed, and when the pan has been removed, an operator may readily reach any 105 part within the chamber 10.

The cylinder block 17 consists in the present instance, of an inner casting 18 and an outer jacket 19 of high tensile strength material, such as steel. The inner casting forms two 110

cylinders 20 and 21 and each cylinder consists of a lower portion 22 and an off-set upper portion 23, the latter, if desired, being of larger diameter, as the upper piston has more weight to lift than the lower piston. The upper and lower portions of each cylinder are integrally connected by a diagonal tubular portion 24, which, as best shown in Fig. 2, has a spark plug opening 25 at one side and an oil pipe opening 26 at its diametrically opposite side, so the portion 24 will form the combustion chamber of the cylinder. The inner casting 18 has a base flange 27, intermediate flanges 28, 29 and 30, and a cap flange 31, the latter forming the top of the cylinder block. The flanges 29 and 30 are spaced apart to provide an exhaust gas passage way 32, which communicates through ports 33 with the upper portions 23 of the cylinders and thus provides means for discharging the exhaust gases.

The flanges 28 and 29 are spaced apart a greater distance to provide a relatively large water chamber 34, which surrounds the compression chambers 24 of the cylinders, and thus permits the water to cool the portions of the cylinders where the heat reaches the maximum.

The flanges 27 and 28 are also spaced apart to provide a large air chamber 35 which leads cold air along the lower portion of each cylinder and discharges the same through ports 36 into the cylinders.

The jacket 19 is preferably made from a short length of steel tubing which is flattened at opposite sides, as shown in Fig. 3, and is drawn upwardly along the inner casting 18 until its upper edge contacts with the cap flange 31, and this jacket has exhaust ports 37 and air inlet ports 38, which respectively communicate with the passage way 32 and the air chamber 35. As best shown in Fig. 3, the jacket is provided at its lower end with outwardly extending lugs 39 apertured to receive threaded rods 40 which secure the cylinder block to the base plate 1. The lower ends of these rods are threaded into the plate 1, as shown at 41 in Fig. 1 and a nut 42 on each rod bears downwardly upon the lug 39. The upper end of each rod passes through an aperture in the cap flange 31 and a nut 43 engages the upper end of the rod and bears upon the last mentioned flange. In dismantling the engine, or taking the cylinder block off of the base plate 1, it is only necessary to remove the rods 40 and to detach devices on the connecting rods, which will be described later on.

Each cylinder contains an upper piston 44 and a lower piston 45, each having a screw threaded socket 46, as shown in Fig. 2. The upper socket 46 is in threaded connection with the lower end of a connecting rod 47 having an eye 48. A lock nut 49 engages the rod 47 for securing the latter against ro-

tation. As shown in Fig. 1, the eye 48 encircles a pin 50, the latter passing through cross bars 51. A washer 52 engages the outer face of one of said cross bars and all of the parts are secured in position by a cotter pin 53, or the like. Reverting again to Fig. 2, it may be seen that each cross bar 51 is provided at its outer ends with detachable pins 54 which rigidly connect the cross bars to the upper ends of the rigid rods 55. These rods are arranged at opposite sides of a plane passing through the axis of each cylinder and the shaft 8, and the lower ends of the rods are rigidly connected by pins 56 to an open frame 57, see Fig. 5. This open frame is shown in detail in Fig. 4 and it has a substantially elliptical aperture 58 provided at its under side with a cam surface 59. As shown in Fig. 2, the frame 57 is arranged within the chamber 10 and its opposite side edges bear against the plates 12, so that the frame, rods 55, rod 47 and pistons 44 and 45 will all move rectilinearly in a vertical plane and the upper piston will be prevented from wobbling and causing a piston slap.

Each lower piston has its socket 46 in threaded connection with a lower rod 60, which is integral with an open frame 61. The rod is held in place by a lock nut 62. The open frame has a downwardly extending cam 63 at its upper side and a concaved cam 64 at its under side. Rings 65 and 66 respectively oscillate in and contact with the open frames 57 and 61, and each of these rings rolls on balls 67, which surround an inner race ring 68.

The shaft 8, for the purpose of the present invention, is of special construction, and it is preferably provided with diametrically opposite semi-circular pieces 69. If only a single cylinder is used, the straight edge of the piece 69 for actuating the upper piston 44 will be located below the shaft when the engine is ready to start its working stroke, and the straight edge of the piece 69 for the lower piston, at the upper side of the shaft 8. Of course, where more than one cylinder is used, the pieces 69 are arranged to move the pistons in the proper sequence.

The shaft 8 has lugs 70 arranged at the points where the pieces 69 are located, and each of these lugs is employed in securing a semi-circular plate 71 adjacent the corresponding piece 69, so that a plate 71 and piece 69 will form an eccentric on the shaft 8, this eccentric holding the inner ring 68 in position. Each plate 71 is detachably secured in position by a screw 72, and it is obvious that when the saddle plates 6 of the shaft bearings 5, are removed and the base plate 1 is lifted upwardly, the operator may readily detach the screws 72 and plates 71 and thus remove the anti-friction bearings from the shaft 8.

An engine constructed in the above manner, will operate on the two-cycle principle,

and as this is so well known, it is deemed unnecessary to describe the specific operation of the engine.

In actual practice I prefer to make each upper piston 44 and its corresponding portion of the cylinder, of larger diameter than the piston 45, as it has more weight to lift than the lower piston.

In a non-reversible engine, the projections 10 on the shaft do not have to be in line with each other, that is on diametrically opposite sides of the shaft, but they can be at angles relatively to one another, so that the pistons may open and close the exhaust ports before 15 other pistons have closed the intake ports, thus allowing surcharging of the cylinders.

Furthermore, if desired, the pieces 69 and plates 71, may form in one case, a disk of larger diameter than the other disk on the 20 shaft, so as to give one piston a longer stroke than the other piston in the same cylinder.

In the present engine, the fuel injection and ignition may be controlled from the rigid rods 55, as the latter operate in unison with 25 all other moving parts of the engine.

In use, the oil pan 16, contains a considerable quantity of oil, and consequently the piston thrusts will be taken up by the frames 57 and 61 which work in said oil bath, and 30 as there is no side thrust on the piston since the piston rods move in rectilinear paths only, piston slap will be eliminated. In the present engine less friction is caused, as all bearings (roller or ball) work in the oil bath, and 35 consequently they will last indefinitely without adjustment, even though the engine works at high speed. Friction is also eliminated due to the heavy rotating parts being balanced, and the reciprocating parts being of light construction.

Furthermore in the present engine, the scavenging air entering through the ports 38 will make a clean sweep through the compression space to the exhaust ports, and thus 45 carbon will be eliminated to a great extent.

From the foregoing, it is believed that the construction, operation and advantages of the invention may be readily understood and it is apparent that changes may be made in 50 the details disclosed without departing from the spirit of the invention as expressed in the claims.

What I claim and desire to secure by Letters Patent is:—

55 1. An internal combustion engine including a cylinder having off-set end portions, a shaft arranged at one end of the cylinder and carrying oppositely disposed eccentrics arranged in close proximity to each other, a 60 pair only of opposed pistons arranged in the off-set portions of the cylinder, and means operatively connecting one piston to one of said eccentrics and the other piston to the other one of said eccentrics.

65 2. An engine including a cylinder having

off-set end portions, opposed pistons in said cylinder, a shaft arranged at one end of the cylinder and provided with diametrically opposite projecting members, rigid frames surrounding said members, a rod rigidly connected to each piston, one of said rods being rigidly connected to one of said frames, and means rigidly connecting the other rod to the other frame.

70 3. An engine including a cylinder having off-set end portions, a shaft arranged at one end of said cylinder, diametrically opposite projections on the shaft, opposed pistons arranged in the cylinder and each having a rigidly connected rod, a frame surrounding one of said projections and rigidly connected to one of said rods, and a second frame surrounding the other projection and rigidly connected to the other rod.

75 4. An engine including a cylinder having off-set end portions, opposed pistons in the cylinder, and each having a rigidly connected rod, a shaft rotatably mounted at one end of the cylinder and provided with projections, a frame around one of said projections 80 rigidly connected to one of said rods, and a second frame around the other projection rigidly connected to the other rod.

85 5. An engine including a cylinder having off-set end portions, opposed pistons arranged 90 in the off-set portions of the cylinder and each having a rigidly connected rod, a rotatable shaft arranged at one end of the cylinder and provided with eccentrics arranged side by side, a rigid frame surrounding each eccentric, anti-friction bearings between each frame and eccentric, one of said frames being rigidly connected to one of the piston rods, and rigid means connecting the other frame to the other one of said rods.

95 6. An engine including a cylinder having off-set upper and lower portions, upper and lower opposed pistons arranged in the off-set portions of the cylinder and each having a rigidly connected rod, a rotatable shaft arranged below the cylinder and having oppositely disposed eccentrics arranged side by side, a ring surrounding each eccentric, anti-friction members arranged between each eccentric and each ring, a frame surrounding each ring and having abutment surfaces to engage the ring, one of said frames being rigidly connected to one of said rods, and means rigidly connecting the other frame to the other one of said rods.

100 7. An engine including a cylinder having off-set end portions, opposed pistons arranged in the off-set portions of the cylinder and each having a rigidly connected rod, a rotatable shaft arranged at one end of the cylinder and having oppositely disposed projections, frames surrounding said projections, one of said frames being rigidly united with one of said rods, and means connecting the other frame to the other rod and including

rigid bars arranged at opposite sides of the axis of the shaft, a cross-head connected to the upper ends of said bars, and means operatively connecting said cross-head to the last mentioned rod.

8. In an engine, a base plate provided with oppositely extending arms and depending bifurcated legs, a shaft, saddle plates connected to said legs and supporting said shafts, plates arranged at opposite sides of the base plate and connecting said legs together, said legs and side plates forming a chamber having an open bottom, and an oil pan closing said bottom.

15. 9. In an engine, a base plate provided with oppositely extending arms and depending bifurcated legs, bearings arranged in the crotches of the legs, a shaft arranged in said bearings, saddle plates detachably holding the bearings in position, side plates detachably connected to the legs and having outwardly extending ledges, and an oil pan detachably connected to the ledges and enclosing the lower portions of the side plates and legs.

10. An explosive engine, including a driven shaft, a cylinder having its end portions offset in the direction of the shaft, oppositely disposed eccentrics mounted on the shaft and arranged in parallel planes coinciding with the axes of the off-set end portions of the cylinder, opposed pistons in the off-set end portions of the cylinder, a frame rigidly united with one of said pistons and operatively engaging one of the eccentrics for driving the latter from one of the pistons, and a second frame rigidly connected to the other piston and operatively engaging the other eccentric

for driving the latter from the last mentioned piston.

11. An internal combustion engine including a cylinder having off-set end portions, a shaft arranged at one end of the cylinder and carrying oppositely disposed eccentrics arranged in close proximity to each other, opposed pistons arranged in the off-set portions of the cylinder, and means including piston rods adapted to move rectilinearly operatively connecting one piston to one of said eccentrics and the other piston to the other one of said eccentrics.

12. An internal combustion engine including a cylinder having off-set end portions, a shaft arranged at one end of the cylinder and carrying oppositely disposed eccentrics arranged in close proximity to each other, opposed pistons arranged in the off-set portions of the cylinder, oppositely disposed rods connected to said pistons, one of said rods being connected to one of said eccentrics and means connecting the other of said rods to the other of said eccentrics.

13. An internal combustion engine including a cylinder having off-set end portions, a shaft arranged at one end of the cylinder and carrying oppositely disposed eccentrics arranged in close proximity to each other, opposed pistons arranged in the off-set portions of the cylinder, a rod connecting one piston to one of said eccentrics, and means including a piston rod, cross-head and connecting rod connecting the other piston to the other one of said eccentrics.

In testimony whereof I affix my signature.

CHAS. REINEKE.
